MEAT GRINDER ATTACHMENT

Hollum B. Shadid, Oklahoma City, Okla.

Application January 17, 1956, Serial No. 39,823

Term of patent 14 years

(Cl. D55—1)

Fig. 1

Fig. 2

Fig. 3

Fig. 4

Figure 1 is a perspective view of a meat grinder attachment, showing my new design;

Figure 2 is a side elevational view thereof;

Figure 3 is a front elevational view thereof; and

Figure 4 is a bottom plan view of the same.

I claim:

The ornamental design for a meat grinder attachment, as shown.
